(57) CLAIM

The ornamental design for a multi-purpose knife, as shown and described.

DESCRIPTION

FIG. 1 is a side front top perspective view of a multi-purpose knife showing my new design;

FIG. 2 is a left side elevational view thereof;

FIG. 3 is a right side elevational view thereof;

FIG. 4 is a front elevational view thereof;

FIG. 5 is a top plan view thereof; and,

FIG. 6 is a bottom plan view thereof.

The broken lines shown in the drawings are for illustrative purposes only and form no part of the claimed design.
